UNITED STATES PATENT OFFICE.

ERIC W. BRANDQUIST, OF ORANGE, NEW JERSEY.

ADJUSTABLE DIMMER.

1,178,292.

Specification of Letters Patent.

Patented Apr. 4, 1916.

Application filed November 16, 1915. Serial No. 81,768.

To all whom it may concern:

Be it known that I, ERIC W. BRANDQUIST, a subject of the King of Sweden, and a resident of Orange, in the county of Essex and State of New Jersey, have invented a new and Improved Adjustable Dimmer, of which the following is a full, clear, and exact description.

This invention relates to dimmers for lamps and particularly to an improved construction which may be readily applied and removed.

The object in view is to provide a dimmer for lamps especially of the automobile type, which may be quickly applied and removed and which also may be adjusted to give different degrees of dimness.

A further object in view is to provide a bodily removable dimmer formed with adjustable sections whereby part of the lamp may be dimmed and the remaining part left uncovered.

In the accompanying drawings:—Figure 1 is a side view of a lamp with certain parts broken away for disclosing an embodiment of the invention; Fig. 2 is a plan view on an enlarged scale of a dimmer embodying the invention; Fig. 3 is a fragmentary sectional view through Fig. 2 on line 3—3, the same being shown on a slightly enlarged scale to that shown in Fig. 2; Fig. 4 is a transverse vertical section through the front part of a lamp disclosing a slightly modified form of the invention to that shown in Fig. 2; Fig. 5 is a plan view of one of the sections of the dimmer shown in Fig. 4.

Referring to the accompanying drawing by numerals, 1 indicates the lamp, which lamp may be of any desired construction and which is provided with the usual door (not shown). Arranged to fit in the lamp, as shown in Fig. 1, is a dimmer 2, which dimmer is held in place by the friction of certain parts, namely, the springs 3 and 4, which springs resiliently press against the sides of the lamp, as shown in Fig. 4. The springs 3 and 4 are preferably provided with an aperture through which a reduced section 5 of the cross bar 6 passes, which reduced section is upset or riveted so as to hold the springs permanently and rigidly in place. The springs are preferably constructed of some high grade material, while the cross bar 6 may be made of cheaper material and flattened at the center for produc-

ing an enlarged bearing 7, said bearing being formed with an aperture 8 through which the pin or bolt 9 passes. The bolt 9 is provided with a head 10 of any suitable structure and a threaded portion 11 for receiving the nut 12. The bar 6 and springs 3 and 4 act as a supporting bar for holding the bolt 9 in position and also the plates 13 and 14 in position, said plates being of some partially opaque or translucent material.

The plates 13 and 14 may be made from metal if desired, so as to shut out all of the light, or may be made from mica, celluloid or other suitable material. When made from mica the same is frosted in some suitable way for making the mica translucent, and when made from celluloid or similar material, coloring matter is preferably used for producing the translucent effect. As shown in Fig. 2, the plates 13 and 14 are slightly more than a half disk so that the entire light may be shut off or dimmed, or if desired a certain part dimmed while the remaining part is left uncovered.

In Figs. 4 and 5 will be seen a slightly modified form of the invention in which a plurality of sections 15 are provided, said sections being formed with an extension 16 having an aperture 17 through which the bolt 9 is arranged to pass. When the sections 15 are adjusted as shown in Fig. 4 and the nut 12 tightened the light will be entirely shut off so that the amount of light allowed to penetrate will be determined by the degree of opaqueness of the sections 15. The nut 12 is intended to lock the plates 13 and 14 in any adjusted position in a manner similar to the way the sections 15 are locked in their adjusted position.

It will be observed that a supporting frame formed by members 3, 4 and 6 will adapt itself to slightly different sized lamps and may be quickly applied and removed at any time while always allowing a quick and easy adjustment of the dimming plates. It will also be observed that the construction does not require any change in the lamp.

What I claim is:

1. In a dimmer of the character described, a dimming plate, and a bar extending across the plate for supporting the plate in a lamp, and a spring at each end of said bar for holding the bar and plate carried thereby in position.

2. In a dimmer of the character described,

a cross bar, a pair of flat springs connected to said cross bar and arranged to frictionally engage the casing of a lamp for supporting the bar, and a dimming plate connected with said cross bar.

3. A dimmer, comprising a supporting cross bar provided with supporting springs, a plurality of adjustable plates, and a clamping member for clamping the plates 10 to said bar in any adjusted position.

4. A dimmer, comprising a supporting cross bar, a plurality of dimming plates formed with apertures therethrough, said bar being also formed with an aperture 15 therethrough, and a bolt extending through said apertures for supporting and clamping said plates in any desired adjusted position.

5. A dimmer, comprising a supporting frame adapted to be bodily applied and removed, said frame comprising resilient supporting springs and a transverse bar connected thereto, said transverse bar having an aperture therein, a plurality of adjust-

able plates having apertures therein, a bolt extending through the apertures in the 25 plates and the aperture in said bar for connecting the plates to said bar and for clamping the plates in any desired adjusted position so as to obscure or cover any part of the light of the lamp to which the device is 30 applied.

6. In a dimmer of the character described, a cross bar, a pair of springs connected to said cross bar adjacent the ends thereof, said springs being arranged to frictionally 35 engage the casing of a lamp for supporting the cross bar, a plurality of adjustable dimming plates, and means for clamping said dimming plates to said cross bar.

In testimony whereof I have signed my 40 name to this specification in the presence of two subscribing witnesses.

ERIC W. BRANDQUIST.
